Assignor to

DES 770

W. & J. Treadwell, Perry & Morton, of same place.

Letters Patent No. 770. Dated March 18th 1856.

The schedule referred to in these Letters Patent and making part of the same

To whom it may concern,

Be it known that I Samuel W. Gibbs of the City of Albany and State of New York have produced a new and original Ornamental design for the plates of an elevated oven cooking stove, said (stove being known to the trade by the name of the Governor) and I hereby declare that the annexed drawings being part of this specification are full and accurate delineations of the said plates with their ornamental parts, the side plate of the stove and the end and side plates of the oven not represented, (one only of each being shewn in the drawings) being symmetrially similar to those represented.

What I claim as my production and desire to secure by letters patent, is the combination and arrangement of ornamental figures and forms represented in the accompanying drawings, forming together the ornamental design for the plates of a cooking stove.
